Harold C. Harvey, Sturgis, Mich., assignor to
Harvey Paper Products Company, Sturgis,
Mich.

Application March 2, 1935, Serial No. 55,686

Term of patent 7 years

To all whom it may concern:

Be it known that I, Harold C. Harvey, a citizen of the United States, residing at Sturgis, in the county of St. Joseph and State of Michigan, have invented a new, original, and ornamental Design for a Liner for Sink Strainers, of which the following is a specification, reference being had to the accompanying drawing, forming part thereof.

Fig. 1 is a plan view,

Fig. 2 is a rear elevational view, and

Fig. 3 is a side elevational view of a liner for sink strainers showing my new design.

I claim:

The ornamental design for a liner for sink strainers, as shown.

HAROLD C. HARVEY.
